Attorney,

UNITED STATES PATENT OFFICE

JAMES WEATHERS, OF INDIANAPOLIS, INDIANA.

SASH-HOLDER.

SPECIFICATION forming part of Letters Patent No. 623,749, dated April 25, 1899.

Application filed October 26, 1898. Serial No. 694,597. (No model.)

To all whom it may concern:

Be it known that I, JAMES WEATHERS, a citizen of the United States, residing at Indianapolis, in the county of Marion and State 5 of Indiana, have invented certain new and useful Improvements in Safety Sash- Locks and Sash-Holders, of which the following is a specification.

This invention relates to improvements in 10 window fasteners and locks; and the object of the invention is to provide a device which will be set into the parting-strip of the window-frame and will operate against the side of the sash to support the latter at any desired 15 position without weights and at the same time lock the sash against possible movement from the outside, either up or down, and to hold it from rattling in its frame by the action of the wind against it.

20 I accomplish the objects of the invention by the mechanism illustrated in the accompanying drawings, in which—

Figure 1 is a view in perspective of a window-frame with a pair of sashes, the same 25 being equipped with my improved sash fastener and lock; Fig. 2, a detail in perspective of the invention removed from the window; Fig. 3, side elevations of the two parts of the device separated from each other; Fig. 30 4, a detail in side elevation of the window-frame with my attachment looking in the direction of the arrows from the line 44 of Fig. 1. Fig. 5 is a like view looking from the line 55 55 of Fig. 1; and Fig. 6 is a modification of 35 the slide, showing a folding handhold.

Like letters of reference indicate like parts throughout the several views of the drawings.

A represents the window-frame, B the lower 40 sash, B' the upper sash, C the inside parting-strip, which holds the lower sash in the frame, and C' the parting-strip between the two sashes, all of which parts are of usual construction.

45 D is the body of my improved fastener and lock and is of the same area and shape in cross-section as that part of the parting-strip which projects beyond or outside of the window-frame. I generally make this body about six 50 inches in length and set it into the parting-strip by removing a corresponding portion of the latter. It becomes a part of the parting-

strip, and as it is of the same size and shape it is scarcely distinguishable from the rest of the strip when painted the same color. It is 55 provided with holes d, by which it is fastened in place by means of screws. The side of this body part D next to the sash is notched and beveled from d' to d'', and in this bevel a centrally-located longitudinal feather or flange 60 D' is provided, the outer edge of which is parallel with the opposite wall of the body, but does not come out flush with the face into which the notch enters.

E is a wedge-shaped piece, which exactly 65 fills out the notch in the body D and will be referred to hereinafter as the "sliding wedge." It is grooved longitudinally and centrally from the sloping face back to the dotted line shown in Fig. 3 to fit over the flange D'. This groove 70 is shown at e. This construction permits the sliding wedge to move longitudinally of the body D; but lateral movement is prevented. The outside face of the wedge may be roughened, as shown at e', to increase the friction 75 between it and the sash. The thick end of the sliding wedge is provided with the handle E', by which it is moved into or out of engagement with the sash.

The excellent feature about this fastener is 80 that it can be applied with equal facility to either the upper or the lower sash.

Applied as shown in Fig. 4, the wedge permits the sash to be raised freely, but impinges between the sash and the body D 85 when the sash is lowered and stops it until the wedge is lifted up by the handle E' and held out of engagement with the sash. Fig. 5 shows the same device upside down to hold a sash against being raised. In practice where 90 it is desired to lock the sash against movement in either direction the device, as shown in Fig. 4, will be placed in the parting-strip on one side of the window, and that shown in Fig. 5 will be placed on the other side of 95 the window.

In the modification shown in Fig. 6 the handle E' is hinged to the wedge in order to allow it to be folded down instead of projecting out so prominently as the solid one does. 100

Having thus fully described my invention, what I claim as new, and wish to secure by Letters Patent, is—

In a window fastener and lock, the body

approximately the same shape and cross-section as the parting-strip of the window having one of its sides beveled and provided with a longitudinal central flange on the beveled side the outer edge of which is parallel with the opposite wall of the body and a wedge sliding on the bevel and grooved to fit the flange, substantially as described and shown.

In witness whereof I have hereunto set my hand and seal, at Indianapolis, Indiana, this 21st day of October, A. D. 1898.

JAMES WEATHERS. [L. S.]

Witnesses:

JOSEPH A. MINTURN,
CARL SCHLEGEL.
